(57) **CLAIM**

I claim the ornamental design for a recliner chair swing, as shown and described.

DESCRIPTION

FIG. 1 of the drawings is a perspective view showing the front, left side, and top of a recliner chair swing embodying the design of my invention;

FIG. 2 is a front elevation view of the recliner chair swing;

FIG. 3 is a right side elevation view;

FIG. 4 is a top plan view;

FIG. 5 is a left side elevation view;

FIG. 6 is a back elevation view; and,

FIG. 7 is a bottom view.
